SENSITIVE SWITCH MECHANISM

Walter L. Dietrich, Hartford, Conn., assignor to
The Arrow-Hart & Hageman Electric Company,
Hartford, Conn., a corporation of Connecticut

Original application August 2, 1949, Serial No.
108,185. Divided and this application Decem-
ber 5, 1950, Serial No. 199,221

16 Claims.

(Cl. 200—76)

1

This invention relates to an electric switch mechanism of the type which requires only a very small amount of movement of the operating member to cause switch actuation. Such switches are therefore sensitive enough to be used in situations where only a minimum degree of movement of the actuating device is available to cause switch operation.

Only one example of a use to which this invention is particularly suited is rotary-cam time-controlled switches for washing machines and the like as is disclosed in my copending application Serial No. 108,185 patented July 15, 1952, No. 2,603,725 of which this application is a division. However, the invention is not limited to such use, its structure and principles being adaptable, with variations within the scope of the invention, to many other uses and situations.

One object of this invention is to provide an improved form of sensitive switch mechanism which is durable and reliable in operation over long periods of use.

Another object is to provide for adjustment of the switch contacts from outside the housing of the whole switch device or from the opposite side of the plate or support on which the sensitive switch mechanism is mounted.

Other objects and advantages of the invention will become apparent as it is described in connection with the accompanying drawing.

In the drawing:

Fig. 1 is a side elevation view of an electric switch embodying the invention, adapted to be operated by a rotary cam actuator.

Fig. 2 is a section view along line 2—2 of Fig. 1 of the invention.

Fig. 3 is a fragmentary detail view of the structure illustrated in Fig. 2 viewed from the opposite side from that of Fig. 2.

Fig. 4 is an enlarged detail section view taken along line 4—4 of Fig. 2.

Fig. 5 is an enlarged perspective detail view of the switch spring compression element.

Referring to the drawing, the switch mechanism may be mounted on any suitable support such as a sheet insulation plate 16. The plate may, if desired, form part of a larger device having a rotary shaft or spindle 22 carrying an insulation cam disc 30 adapted to engage a roller 64 on an axle 63 transversely mounted between parallel arms 62a, 62c of a lever designated generally by numeral 62.

The free ends of the lever arms 62a, 62c may be joined by an integral strut 62s. Their opposite ends are pivotally mounted on a U-shaped metal

supporting bracket 60 whose transverse part 60a is riveted to the plate 16. The strut 62s is engaged by an adjustable plunger arrangement which reciprocates when moved by the lever 62 so as to control the operation of the movable contact. The movable contact comprises a thin, flexible leaf spring member 65 which is stamped from sheet metal with an H-shaped opening therein as illustrated in Fig. 2. Flexible apertured arms 65a and 65b, formed by the stamping out of the movable contact member, are in the plane of the contact member as stamped. However they are later stressed or bowed upwardly by the insertion between them of a compression member 66 of substantially U-shape and stamped from thin flexible sheet metal with slots 66s in its arms to receive the ends of the arms 65a, 65b. The compression member 66 is mounted on the plunger as hereinafter more fully described.

Movement of the arms 65a and 65b through the plane of the contact member 65 from one side to the other thereof causes snap action movement of the ends of the contact member 65 also with a snap-action in a manner now well understood by those familiar with the art. At the ends of the contact member are contact buttons 67 to engage and disengage fixed contact buttons 68 mounted on fixed contact members 69. The fixed contact members have rivet extensions 69a passing through the insulating plate 16 and through a metal terminal plate 70 on the outside of the insulating plate. Between the fixed contact member 69 and the inside surface of the insulating plate 16 is located one leg of a rigid stop member 71 stamped from sheet metal into substantially J-shape. By peening over the ends of the rivet portion 69a, the stop member 71, fixed contact 69 and terminal member 70 are thus secured to the plate 16. The portion 71s of the stop member 71 overlies the end of the movable contact to limit the switch opening or disengaging movement of the movable contact member at each end, it being understood that similar fixed contact structure and stop members are provided at each end of the movable contact as well illustrated in Figs. 1 and 4.

It is desirable to be able to adjust for accuracy the position of the movable switch contact and thus its action from the outside of the switch housing. For this purpose the plunger device is constructed in the following manner. A support or bearing member 72 is mounted in the insulating plate 16. This bearing member has a flange 72a abutting the outside surface of the plate 16 and a similar interior flange 72c

which is stamped down upon the interior surface of the plate 16 to secure the bearing member permanently in place. The bearing member has a bore which is reduced near its outer end to form a shoulder against which presses one end of a compression spring 73. The other end of such spring 73 presses against a shoulder on a sleeve member 14 whose outwardly facing end 14a is of reduced diameter and slides in the smaller part of the bore in the bearing member 12. The inner end of the sleeve member 14 slides within the larger portion of the bore in the member 12.

Upon the larger or inner end 14b of the sleeve member is secured the compression member 66. The compression member is secured by upsetting an extending neck 14b of the sleeve end 14b onto the inside surface of the transverse portion 66t of the compression member.

The adjustment of the position of the movable contact is accomplished by manipulating a screw bolt 75 which slides within the sleeve 14 and has its inner end extending inwardly of the switch housing to engage the lever 62. A square-headed nut 76 is threaded upon the end of the screw bolt 75 to fix the adjustment and to determine the inward movement or location of the screw bolt into or relatively to the sleeve member. The abutment of the nut 76 against the sleeve 14 thus limits the movement of the screw bolt 75 into the sleeve. To maintain the adjustment, parallel lugs 62g are struck down from the lever strut 62s in position to embrace the sides of the nut. A slot is provided in the head of the bolt. This slot is available from the outside of the plate 16 by use of a small screw driver inserted in the sleeve 14. By turning the bolt a relatively fine adjustment can be obtained of the action of the switch. This is desirable in many uses of the switch, only one example of which is when the controlling cam is rotated by clockwork. In such case it is desirable that the switch operate precisely at the time set. Thus, a fine adjustment is needed.

Many modifications within the scope of my invention will occur to those skilled in the art. Therefore I do not limit it to the specific embodiments illustrated and described.

What is claimed is:

1. In a sensitive switch, a support, a fixed contact member, a movable contact member having a stressed portion, an actuating member, a member slidible in said support for moving said movable contact member with a snap action to engage and disengage said fixed contact member, an adjustable connection between said actuating member and said slidible member comprising an adjustable member movable in said slidible member and acted upon by said actuating member, and a member engageable with said slidible member and mounted on said adjustable member maintaining the adjustment of the latter.

2. In a sensitive switch, a support, a fixed contact member, a movable contact member having a stressed portion, an actuating member, a member slidible in said support for moving said movable contact member with a snap action to engage and disengage said fixed contact member, an adjustable connection between said actuating member and said slidible member comprising an adjustable member movable in said slidible member and acted upon by said actuating member, and a member engageable with said slidible member and mounted on said adjustable member maintaining the adjustment of the latter, said actuating member moving said movable contact

into one position, and biasing means acting on said slidible member to move the movable contact into the other position.

3. A device as claimed in claim 1 wherein the contact members and actuating means are located on one side of the support, and said adjustable member extends through the support for adjustment from the opposite side of said support.

4. A device as claimed in claim 1 having means on said actuating member to prevent rotation of the member which is on said adjustable member.

5. A device as claimed in claim 3 wherein the contact member and actuating means are located on one side of a support, and said adjustable member extends through the support for adjustment from the opposite side of said support.

6. In a sensitive switch, a fixed contact member, a movable contact member having a stressed portion, an actuating member for moving said movable contact member with a snap action to engage and disengage said fixed contact member, an adjustable connection between said actuating member and said movable contact comprising a member engaging with said actuating member and a member threaded upon and adjustable upon said engaging member for varying and determining the position of the actuating member and movable contact member relative to one another, and a sleeve member biased to cause operation of the movable contact member into one position, said adjustable member sliding within said sleeve member.

7. A device as claimed in claim 6 mounted on one side of support, said adjustable member being available for adjustment from the other side of the support.

8. In a sensitive switch comprising an insulating support, an actuating member on one side of the support, fixed contacts mounted on said side of the support, a bridging contact member on said side of the support engageable with said fixed contacts, means cooperating with said actuating member and with said bridging contact member to cause it to move overcenter and to operate with a snap action, said means comprising a nut, a sleeve member movable by said nut, an adjusting bolt slidible in said sleeve member and engaged with said nut, a mounting member mounted in said insulating support, and means to bias said sleeve, said bolt being adjustable from the opposite side of said support from said actuating member.

9. In a sensitive switch, a support, a fixed contact member, a movable contact member having a stressed portion, a member slidible in said support for moving said movable contact member with a snap action to engage and disengage said fixed contact member, an actuating member, an adjustable connection between said slidible member and said actuating member comprising a screw bolt passing through said slidible member, one end of said bolt being accessible for adjusting the bolt from one side of said support, the other end of said bolt being on the other side of said support and being moved by said actuating member.

10. A sensitive switch as claimed in claim 9 including a spring means biasing said slidible member and bolt toward said actuating member.

11. In a sensitive switch, a support, a fixed contact member, a movable contact member having a stressed portion, a bearing member mounted in said support, a sleeve member slidible in said bearing member for moving said movable contact member with a snap action to engage and

disengage said fixed contact member, an actuating member, an adjustable connection between said slideable member and said actuating member comprising a screw bolt passing through said slideable member, one end of said bolt being accessible for adjusting the bolt from one side of said support, the other end of said bolt being on the other side of said support and being moved by said actuating member.

12. A sensitive switch as claimed in claim 11 including spring means within said bearing member biasing said sleeve member and bolt toward said actuating member.

13. In a sensitive switch, a support, a fixed contact member, a member slideable in said support, a movable contact member carried by said slideable member and having a stressed portion whose condition may be varied to cause engagement and disengagement of the fixed and movable contact members with a snap action, an actuating member, an adjustable connection between said slideable member and said actuating member comprising a screw bolt passing through said slideable member, one end of said bolt being accessible for adjusting the bolt from one side of said support, the other end of said bolt being on the other side support and being moved by said actuating member.

14. A sensitive switch as claimed in claim 13 wherein the slideable member is a sleeve, and spring means biasing said sleeve toward said actuating member.

15. In a sensitive switch, a support, a fixed contact member, a movable contact member having a stressed portion, a member slideable in said support for moving said movable contact member with a snap action to engage and disengage said fixed contact member, an actuating member, an adjustable connection between said slideable member and said actuating member comprising an adjustment member passing through said slideable member, one end of said adjustment member being accessible for adjusting it from one side of

said support, the other end of said adjustment member being on the other side of said support and being moved by said actuating member, and means between said adjustment member and slideable member to adjust them in different relative positions.

16. In a sensitive switch, a support, a fixed contact member, a movable contact member having a stressed portion, a bearing member mounted in said support, a sleeve member slideable in said bearing member for moving said movable contact member with a snap action to engage and disengage said fixed contact member, an actuating member, an adjustable connection between said slideable member and said actuating member comprising an adjustment member passing through said slideable member, one end of said adjustment member being accessible for adjusting it from one side of said support, the other end of said adjustment member being on the other side of said support and being moved by said actuating member, and means between said adjustment member and slideable member to adjust them in different relative positions, and spring means within said bearing member biasing said sleeve member and adjustment member toward said actuating member.
